UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

TYPE-WRITING MACHINE.

1,249,022.

Specification of Letters Patent.

Patented Dec. 4, 1917.

Application filed September 30, 1915. Serial No. 53,220.

To all whom it may concern:

Be it known that LEE S. BURRIDGE, deceased, late a citizen of the United States, and late residing in the borough of Manhattan, county, city, and State of New York, invented certain new and useful Improvements in Type-Writing Machines, of which the following is a specification.

The present invention relates to ribbon-feeding and vibrating mechanism for type-writing machines. More particularly the invention relates to mechanism, of this character, in a typewriting machine in which the platen is carried on a frame shiftable 15 between two or more case-positions on the main frame.

An object of the invention is to have the ribbon-feeding and ribbon-vibrating mechanisms of such construction that they may be 20 in large part mounted on the shiftable platen frame in a compact and convenient manner; the parts being readily accessible for setting and assembling, simple in operation, and of inexpensive manufacture. A

25 feature of the invention is a novel connection of the ribbon mechanisms, on the shiftable platen frame, to a universal bar, on the main frame, operable at type-strokes; the connection being flexible or capable of 30 accommodating itself to the different case-positions of the platen frame, so that the ribbon mechanisms need at no time be disconnected from the universal bar. A feature of the invention concerns the manner

35 in which, for simplicity, certain of the operating connections are made common to both the ribbon-feeding and ribbon-vibrating mechanisms. A feature of the invention is the construction and manner of shifting the 40 platen frame, whereby the proper relations of the ribbon mechanisms to the platen are maintained in all case-positions of the platen without complicated parts or movements.

45 The manner in which the ribbon vibrator is supported for oscillation at type-strokes, and in which this support is adjustable relatively to the vibrator to shorten or lengthen the effective ribbon-throwing arm of the vibrator, is made the subject-matter of my di-

visional application 151,173, filed February 27, 1917, as well as the provision for locking the vibrator support in any adjusted position thereof.

Other objects of the invention are: a novel 55 mechanism for feeding the ribbon by a drive of either of the ribbon spools, according to the direction of feed; a mechanism for rendering operative or inoperative either of the spool-driving mechanisms; and a device 60 by means of which, in reversing the direction of ribbon feed, the driving mechanism at one spool is rendered operative and that at the other spool simultaneously rendered 65 inoperative.

In a preferred form of the invention, the platen frame is shiftable substantially rectilinearly between case-positions, so that the platen and the ribbon-vibrating and feeding mechanisms all have practically the 70 same movement, and maintain their relative positions.

Other features and advantages will hereinafter appear.

In the accompanying drawings,

75 Figure 1 is a top plan view, partly broken, of the ribbon-feeding and ribbon-vibrating mechanisms, and of the frames on which the same are mounted.

Fig. 2 is a view in front elevation of the 80 ribbon-carrier and of certain of the connections for vibrating the same; a part of the platen, the type-guide, and a ribbon-guide being also shown.

Fig. 3 is a view in cross-sectional side elevation through the machine frames, showing the ribbon-feeding mechanism and the connections to the same from the type-keys.

Fig. 4 is a detail view in longitudinal cross-section through one of the links which 90 connect the ribbon-feeding mechanism to the universal bar.

Fig. 5 is a view in side elevation of the ribbon-vibrator, and of its connections to the ribbon-carrier, and to the lever by means of 95 which it is actuated.

Fig. 6 is a view in cross-sectional elevation through one of the ribbon spools and the mechanism for feeding the same.

The platen 10 is journaled in a frame 11 100

which has letter-feed and return movement on a frame 12. The frame 12 is connected to the main frame 13 by links 14 at each side thereof, and is shiftable up and down thereon between case-positions, of which there may be three, as shown and described in my co-pending application for Letters Patent, Serial No. 52,594, filed September 27th, 1915. The type keys 15 are on levers 16 fulcrumed on a blade 17 carried by the main frame. Each type key is held to its fulcrum, and is also returned to normal position after each operation thereof, by a spring 18 which is attached at one end to a finger 19 on the key lever and at the other end at 20, to the rear of the key lever, and which is bent over a plate 21 on the main frame, so that the spring, in tending to straighten itself, exerts an upward pressure on the key lever. A plate 22 also restricts movement of the key levers away from the blade 17. The key lever operates in a slot 23 in a front plate 24 of the main frame; and the upper and lower walls of the slot 25 determine the throw and normal position of the key lever. Each type key lever has a shoulder 25 thereon, adapted, upon depression of the key, to engage and depress a universal bar 26 pivoted at 27 in arms 28 on the main frame. A suitable spring (not shown) returns the universal bar to normal position when the key is released, and a suitable stop (not shown) determines the normal position of the universal bar and other parts 30 connected thereto.

To ears 30 on the side plates 31 of the shiftable platen frame 12, are secured cups 32, one at each side of the machine, to receive the ribbon spools 33 and 34. Journaled in ears 37 and 39 of brackets secured by screws 38 to the side plates 31 of the platen frame are shafts 35, onto each of which one of the spools is adapted to be placed for rotation therewith. Each shaft 35 is interiorly threaded to receive a screw 36, the head of which holds the shaft against longitudinal displacement upward. Fast to each shaft 35 is a hub 40, and fast to each hub is a disk 41 carrying a pin 42, which projects upward and is adapted to enter a hole 43 in the lower end-plate 44 of the spool when the spool is slipped down over the shaft and is turned thereon to bring the hole 43 into registration with the pin 42. The spool and hub 40 are thus interlocked for rotation together. A spring 46, attached at 47 to the interior of the shaft, carries a ball 48, which a bend in the spring tends to throw laterally. The spring yields to permit the ball to press through the spool bearing, but when the spool is seated, the ball snaps over to engage the upper end-plate 49 of the spool, thus holding the spool against accidental upward displacement on the shaft. The ribbon 50 is led from one spool to the

other through openings 51 in the spool cups, and between the lips 51^a and 51^b of a guide piece 52 secured by screws 52^a to the base of the cups 32. The cups 32 have large openings 32^a in the base thereof to permit them to be set in place over the shafts 35 and attached parts.

Fast to each hub 40 is a ratchet wheel 53, by means of which the spool is turned step by step at type strokes. Loose on each shaft 35, between the bracket-ear 39 and a washer 55, is an arm 54; and pivoted to the end of the arm 54 is a pawl 56, held resiliently in engagement with the teeth of the ratchet wheel by a spring 57, for turning the ratchet wheel when the arm 54 is vibrated. Pivoted to the base of the cup 32 (see Fig. 3), and held resiliently to the ratchet wheel by a spring 58, is a pawl 60 for holding the ratchet wheel when the pawl 56 is returning to normal position after each feed.

Each arm 54 has depending therefrom a pin 61 which lies between two prongs 62, offset horizontally on the end of a lever 63, pivoted at 64, at an intermediate point 90 thereof, to the bracket ear 37. Pivottally connected to the lower arm of each lever 63 is a link 65, the other end of which connects to an arm 66, fast to a rock-shaft 67, journaled in bracket arms 68, which are secured to a cross plate 69 of the main frame near each side thereof, (see Fig. 1). Also fast to the shaft 67 is an arm 70, connected by a link 71 to the universal bar. Depression of the universal bar by a type key therefore rocks the shaft 67, to throw forward the links 65 and rock the levers 63, thus effecting a one-step feed of the ribbon. The universal bar, in returning to normal position, also returns the levers 63 and pawl-carrying arms 54 to normal position. A preferred means for connecting the link 65 to the lever 63, and one which permits of ready separation and union of the two, is shown in Figs. 4 and 6, in which a pivot pin 63^a fast to the link 65 passes through a bearing hole in the lever 63, and through a spring strip 65^a attached to the link 65. The spring 65^a prevents accidental disconnection of the lever 63 and link 65, but yields to permit of withdrawal of the pin 63^a from the lever 63 when proper force is applied. It will be noted that the link 65 maintains the connection of the arm 66, on the main frame, to the lever 63, on the platen frame, in all case-positions, and during the shift, of the latter. A shift of the platen frame, merely causes the lever 63 and link 65 to assume a different angular position, and the pawl 56 to be moved slightly to a different set position on the ratchet wheel; the operation of the parts at type strokes is not changed.

The ribbon may be fed in either direction; and the direction of feed may be reversed when desired. While one spool is

effecting the feed, the pawl 56 at the other spool is held out of engagement with the ratchet wheel at that spool, and vibrates idly at type strokes. It will be noted (see 5 Fig. 1) that the pawls 56 and 60 at the right-hand spool are arranged to feed that spool in clockwise direction, whereas the pawls at the left-hand spool are arranged for effecting a feed in counter-clockwise direction. For holding the pawl idle at one spool while the feed is effected at the other, there is, on each shaft 35, a cam plate 72 having a hub portion 55 and held in place by the washer 55^a between the hub 40 and 10 the pawl carrying arm 54. Each cam plate is adapted to be turned on the shaft, and has a cam surface 73 and a dwell 74, by means of which, when the cam is turned in the proper direction, the pawl 56 is forced out 15 of the ratchet wheel, and held away from the same, (see the right-hand spool in Fig. 1). Each cam plate also has a cam surface 75 and a dwell 76 for similarly and simultaneously throwing and holding the back-check pawl 60, thus leaving the spool free 20 to turn as the ribbon is drawn off it by the feeding action of the other spool. The cam surfaces 73 and 75 at one spool are inclined oppositely to those at the other spool, so 25 that when the cams are swung in the same direction, one disengages the pawls from the ratchet wheel, while the other releases the pawls to the springs which throw them into the ratchet wheel.

30 35 For operating the cam plates, each has integral therewith an arm 77, from which depends a pin 78. Pivoted at 79 to the front plate 24 of the main frame, opposite each spool, is an arm 80, the free end of 40 which has an offset, horizontal finger 81 which is forked to embrace loosely the depending pin 78 on the adjacent cam plate. The pins 78 are of such length that the engagement of the same with the forked fingers 81 is maintained in all case-positions 45 of the platen. One of the arms 80 also carries a finger piece 82, by means of which it may be rocked to throw the cam plate in one or the other direction. The two 50 arms 80 are connected by a link 83, so that both cam plates may be thrown simultaneously in reversing the direction of feed of the ribbon.

55 Between the spools, and just to the left 55 of a type guide 84 on the segment 85, at printing point, the ribbon is threaded through an eye or slot 86^a in a carrying arm 86. At the right of the printing point, the ribbon is held and guided between two 60 spring clips 87 and 88 secured to the platen frame. The clip 88 may also serve as a paper guide. The carrier 86 is vibrated at type strokes, (except in stenciling), to 65 present the ribbon to the printing point, and thereafter to return it to a normal po-

sition below the printing point. The carrier is shown as a strip of sheet metal turned on itself to have a part 89, by means of which it is braced for rigidity. The carrier is on a pivot pin 90 held in ears on 70 a bracket 91 secured to the left-hand side plate 31 of the shiftable platen frame. Its point of support thus maintains the same position with respect to the platen in all case-positions of the latter. The normal, or 75 nonprinting, position of the carrier, (shown in full lines in Fig. 2), is determined by contact of a stop finger 92 on the carrier against the side plate of the platen frame. For shifting the carrier at type strokes, to the 80 dotted line position in Fig. 2, to present the ribbon to the printing point, there is a link 93, one end of which hooks into a hole 86^b in the carrier, and the other end of which connects with a vibratory plate 94 on a 85 bracket arm 95 secured to a cross plate 96 forming part of the shiftable platen frame. The bracket arm 95 may also be braced from the side plate 31 of the platen frame by a strip of metal 97. The plate 94 is slot- 90 ted at 98 to engage a pin 99 on the bracket 95; and pivoted on the pin 99 is a link 100, pivotally connected by a pin 101 to a link 102. When the parts are set for printing, as distinguished from stenciling, the pin 101 95 also lies in the slot 98, so that reciprocation of the link 102 causes the plate 94 to be rocked, (for example, between the full and dotted line positions of Fig. 5), thereby causing the carrier to be moved up and 100 down with the ribbon. A pin 103 on an arm 104 pivoted to the bracket 95, by engagement with another slot 105 in the plate 94, controls and guides the plate 94 in its 105 vibratory movements. The link 102 is pivotally connected at 106 to the lever 63 which operates the ribbon-feeding mechanism, and which, it will be remembered, is connected to the universal bar 26 to be vibrated by the latter at type-strokes. This connection, 110 it will also be remembered, is maintained in all case-positions of the platen, and during the shifting operations. For connecting the link 102 to the lever 63, the latter may have an ear 116 offset from the end thereof, and 115 to this ear the link 102 may be held by a spring such as 65^a (see Fig. 4).

120 The ribbon may be a bichrome ribbon, having, for instance, an upper black zone, and a lower red zone; and therefore requiring a longer throw at type-strokes to present the red zone, than to present the black zone, to the printing point. For stenciling, no throw of the ribbon is desired. There are therefore three settings of the 125 ribbon vibrator, and the action thereof depends upon the position of the pins 99 and 101 in the slot 98 of the plate 94. This change of position of the pins is effected by shifting the plate on its supporting arm 130

95; and for this purpose, the arm 104, which carries the pin 103 in the slot 105, forms part of a finger lever 107 pivoted at 108 to the bracket 95. If the lever 107 be moved 5 to the right from Fig. 5 position, the pin 103 shifts the plate 94 downward and at the same time effects an angular shift of the same to the right, thereby causing the pin 101 to pass from the slot 98 into a slot 109, 10 which, in this position of the plate, will extend in the direction of reciprocation of the link 102. Reciprocation of the link 102, when the plate 94 is so shifted, results in 15 back and forth movement of the pin 101 in the slot 109 without vibration of the plate 94 or of the ribbon carrier; and the parts are thus set in so-called neutral position for stenciling. If, on the other hand, the finger lever 107 is moved to the left from Fig. 5 20 position, the pin 103 will cause the plate 94 to be lifted, and at the same time shifted angularly to the left, leaving both pins 99 and 101 in the slot 98, but with a longer arm from the pin 101 to the point of connection 25 of the link 93 to the plate, and also providing for a greater angular throw of the plate 94 when the latter is vibrated. This last setting of the plate 94 therefore provides for a greater movement of the ribbon carrier at type strokes than when the parts are 30 set as in Fig. 5, and is the setting for printing from the red zone of the ribbon. The Fig. 5 setting is the setting for printing from the black zone of the ribbon.

35 For locking the plate 94 in any of its settings the finger lever 107 has an extension 110 with three recesses 111^a, 111^b, and 111^c in its edge. Adapted to engage the part 110 in any one of these recesses, according to the 40 angular position of the lever 107, is a pin 112 carried by an arm 113, pivoted at 114 to the bracket 95. A spring 115, connecting the arm 113 to the bracket 95, holds the pin 112 in whichever of the recesses it registers 45 with, and prevents accidental displacement of the lever 107 and plate 94. The pin 112 is cammed out by the teeth when the lever 107 is thrown to re-set the plate 94.

50 All parts of the ribbon vibrating mechanism, and of the mechanism for setting the ribbon for different colors, and for stenciling, are seen to be carried by the shiftable platen frame, excepting only the connections from the lever 63 to the universal 55 shaft; and even these last connections are at all times maintained unbroken. A shift of the platen frame, as pointed out, changes the angular position of the lever 63, and in so doing shifts the link 65 somewhat; and 60 the link 65 in shifting, may change somewhat the setting of the plate 94. This last change is not sufficient, however, to affect the described operations of the mechanisms at type strokes.

65 Variations may be resorted to within the

scope of the invention, and portions of the improvements may be used without others.

Having thus described my invention, I claim:

1. In a typewriting machine, a main frame, a platen frame shiftable between case-positions on the main frame, a platen, type keys on the main frame, supports for ribbon spools on the shiftable platen frame, and means for effecting a feed of the ribbon 75 from one spool to the other at type strokes, comprising a toothed wheel, a dog for driving said wheel step by step, a vibratory arm by which said dog is actuated, a lever pivoted to the platen frame and connected to 80 said arm, a universal bar on the main frame, a connection from the universal bar to said lever, and means whereby said universal bar and connected parts are vibrated by the type keys at type strokes. 85

2. In a typewriting machine, a main frame, a platen frame shiftable between case-positions on the main frame, a platen, type keys on the main frame, supports for ribbon spools on the shiftable platen frame, 90 and means for effecting a feed of the ribbon from one spool to the other at type strokes, comprising a toothed wheel, a dog for driving said wheel step by step, a vibratory arm by which said dog is actuated, a lever pivoted to the platen frame and connected to 95 said arm, a universal bar on the main frame, a link pivotally connected to the universal bar and to said lever, and means whereby said universal bar and connected 100 parts are vibrated by the type keys at type strokes.

3. In a typewriting machine, a main frame, a platen frame shiftable between case-positions on the main frame, a platen, 105 type keys on the main frame, supports for ribbon spools on the shiftable platen frame, and means for effecting a feed of the ribbon from one spool to the other at type strokes, comprising a toothed wheel, a dog for driving said wheel step by step, a vibratory arm by which said dog is actuated, a lever pivoted to the platen frame and connected to 110 said arm, a universal bar on the main frame, a rock-shaft on the main frame, a connection 115 from the universal bar to said shaft for rocking the latter, an arm fast to said shaft, a link connecting said arm to the lever on the platen frame, and means whereby the universal bar is actuated by the type 120 keys at type strokes.

4. In a typewriting machine, a main frame, a platen frame shiftable between case-positions on the main frame, a platen, type keys on the main frame, supports for 125 ribbon spools on the shiftable platen frame, and means for effecting a feed of the ribbon from one spool to the other at type strokes, comprising a toothed wheel, a dog for driving said wheel step by step, a vi 130

bratory arm by which said dog is actuated, a lever pivoted to the platen frame and connected to said arm, a universal bar on the main frame, a bell-crank on the main frame, 5 a connection from the universal bar to one arm of the bell-crank, a link connecting the other arm of the bell-crank to the lever on the platen frame, and means whereby the universal bar is actuated by the type keys 10 at type strokes.

5. In a typewriting machine, a platen, type keys, supports for ribbon spools, and means for effecting a feed of the ribbon from one spool to the other, comprising a vibratory arm for effecting a step-by-step drive of one of said spools, a lever connected to said arm, a universal bar, a bell-crank, a connection from the universal bar to one arm of the bell-crank, a link connecting the 15 other arm of the bell-crank to said lever, and means whereby the universal bar is actuated by the type keys at type strokes:

6. In a typewriting machine, a main frame, a platen frame shiftable between 25 case-positions on the main frame, a platen, type keys on the main frame, supports for ribbon spools on the shiftable platen frame, and means for effecting a feed of the ribbon from either spool to the other at type 30 strokes, comprising two toothed wheels each for driving one of said spools, two dogs each for effecting a step-by-step drive of one of said wheels, two vibratory arms each for actuating one of said dogs, two levers pivoted to the platen frame each connected to one of said arms, a universal bar on the main frame, a rock-shaft on the main frame, two arms fast to said shaft, two links each connecting one of said arms on the shaft 40 to one of said levers on the platen frame, a connection from the universal bar to said shaft for rocking the latter, means whereby the universal bar is actuated by the type keys at type strokes, and means for rendering one of said dogs inoperative when the other is operative.

7. In a typewriting machine, a main frame, a platen frame shiftable between 45 case-positions on the main frame, a platen, type keys on the main frame, ribbon feeding mechanism on the platen frame, a universal bar on the main frame, means whereby the universal bar is actuated by the type keys at type strokes, and a connection from the universal bar to said ribbon feeding mechanism on the platen frame for operating ribbon feeding mechanism when the universal bar is actuated, said last connection comprising a link shiftable with the platen frame while maintaining its operative relation to the universal bar and ribbon feeding mechanism in all case-positions of the platen frame.

8. In a typewriting machine, a main 55 frame, a platen frame shiftable between

case-positions on the main frame, a platen, type keys on the main frame, ribbon feeding mechanism on the platen frame, a universal bar on the main frame, means whereby the universal bar is actuated by the type 70 keys at type strokes, and a connection from the universal bar to said ribbon feeding mechanism on the platen frame for operating ribbon feeding mechanism when the universal bar is actuated, said last connection 75 comprising a link which is rocked to another setting when the platen frame is shifted, so as to maintain the connection of the universal bar to the ribbon feeding mechanism on the platen frame in all case-positions of the latter.

9. In a typewriting machine, type keys, mechanism for feeding a ribbon from either of two spools to the other, comprising, at each spool, a toothed wheel for driving the 80 spool, a dog for driving the wheel, means for holding the dog to the wheel, means for actuating the dog at type strokes, a cam movable in one direction to hold the dog from the wheel and movable in the other 85 direction to release the dog for engagement thereof with the wheel, a rock-arm connected to each cam, a link connecting the two rock-arms, and means for shifting the link longitudinally; said dogs being arranged to 90 drive the wheels in opposite directions, and said cams being so arranged that when said link is shifted, the cam at one wheel operates to hold the dog from the wheel, and the cam at the other wheel operates to release the dog for engagement thereof with 95 the wheel.

10. In a typewriting machine, a main frame, a platen frame shiftable thereon between case-positions, type keys on the main 105 frame, a ribbon feeding mechanism on the shiftable platen frame, a ribbon vibrating mechanism on the shiftable platen frame, a rock-shaft on the main frame, connections from said ribbon feeding and vibrating 110 mechanisms to said rock-shaft, and connections from the type keys to said rock-shaft for rocking the latter at type strokes to actuate said ribbon feeding and vibrating mechanisms.

11. In a typewriting machine, a main frame, a platen frame shiftable thereon between case-positions, type keys on the main frame, a ribbon feeding mechanism on the shiftable platen frame, a ribbon vibrating mechanism on the shiftable platen frame, a universal bar on the main frame, connections from said ribbon feeding and vibrating mechanisms on the platen frame to said universal bar on the main frame, 120 and means whereby the universal bar is actuated at type strokes to operate said ribbon feeding and vibrating mechanisms, said connections intermediate the universal bar and said ribbon mechanisms being flexible 125 130

so as to be maintained in all case-positions of the platen.

12. In a typewriting machine, a main frame, a platen frame shiftable thereon between case-positions, type keys on the main frame, a ribbon feeding mechanism on the shiftable platen frame, a ribbon vibrating mechanism on the shiftable platen frame, a universal bar on the main frame, connections from said ribbon feeding and vibrating mechanisms on the platen frame to said universal bar on the main frame, and means whereby the universal bar is actuated at type strokes to operate said ribbon feeding and vibrating mechanisms, said connections intermediate the universal bar and said ribbon mechanisms comprising a link which is free to swing in the case-shifting operation so as to maintain its relation to the ribbon mechanisms on the one hand, and to the universal bar on the other hand, in all case-positions of the platen.

13. In a typewriting machine, a main frame, a platen frame shiftable between case-positions on the main frame, type keys on the main frame, a ribbon vibrating mechanism on the shiftable platen frame, a ribbon feeding mechanism on the shiftable platen frame, a lever on the shiftable platen frame, connections from the type keys to said lever for rocking the lever at type strokes, and connections from said lever to the ribbon vibrating and feeding mechanisms for actuating the latter.

14. In a typewriting machine, a main frame, a platen frame shiftable between case-positions on the main frame, type keys on the main frame, a ribbon vibrating mechanism on the shiftable platen frame, a lever on the shiftable platen frame, connections from the type keys to said lever for rocking the lever at type strokes, and a link from said lever to the ribbon vibrating mechanism for actuating the latter.

15. In a typewriting machine, a main frame, a platen frame shiftable between case-positions on the main frame, type keys on the main frame, a ribbon vibrating mechanism on the shiftable platen frame, a universal bar on the main frame, a bell crank on the main frame, a link connecting one arm of said bell crank to the ribbon vibrating mechanism on the platen frame, a connection from the universal bar to the other arm of said bell crank, and means

whereby the universal bar is actuated by the type keys at type strokes.

16. In a typewriting machine, a main frame, a carriage-supporting frame shiftable between case-positions on the main frame, ribbon-feeding mechanism on the shiftable frame, type keys, a universal bar on the main frame actuated by the type keys, and a flexible connection from the universal bar for actuating the ribbon-feeding mechanism on the shiftable frame at type strokes in all case-positions of the shiftable frame.

17. In a typewriting machine, a main frame, a carriage-supporting frame shiftable between case-positions on the main frame, ribbon-feeding mechanism on the shiftable frame, type keys, a universal bar on the main frame actuated by the type keys, a rock shaft on the main frame, a connection from the universal bar for rocking said shaft at type strokes, an arm fast to the rock shaft, and a connection from said arm to the ribbon-feeding mechanism on the shiftable frame.

18. In a typewriting machine, a main frame, a carriage-supporting frame shiftable between case-positions on the main frame, ribbon-vibrating mechanism on the shiftable frame, type keys, a universal bar on the main frame actuated by the type keys, and a flexible connection from the universal bar for actuating the ribbon-vibrating mechanism on the shiftable frame at type strokes in all case-positions of the shiftable frame.

19. In a typewriting machine, a main frame, a carriage-supporting frame shiftable between case-positions on the main frame, ribbon-vibrating mechanism on the shiftable frame, type keys, a universal bar on the main frame actuated by the type keys, a rock shaft on the main frame, a connection from the universal bar for rocking said shaft at type strokes, an arm fast to the rock shaft, and a connection from said arm to the ribbon-vibrating mechanism on the shiftable frame.

FRANCIS O. BURRIDGE.
*Executor of the last will and testament of
Lee S. Burridge, deceased.*
